UNITED STATES PATENT OFFICE.

ZOPIE A. VIŠEK, OF ORD, NEBRASKA.

DESIGN FOR A CANDELABRUM.

49,735.

Specification for Design.

Patented Oct. 3, 1916.

Application filed April 28, 1916. Serial No. 94,277. Term of patent 3½ years.

To all whom it may concern:

Be it known that I, ZOPIE A. VIŠEK, a citizen of the United States, residing at Ord, in the county of Valley and State of Nebraska, have invented a new, original, and ornamental Design for Candelabra, of which the following is a specification, reference being had to the accompanying drawing, forming part thereof.

Figure 1 illustrates a front elevation of my new design. Fig. 2 illustrates a bottom view looking in direction of 2—2.

I claim:

The ornamental design for a candelabrum, as shown.

In witness whereof, I have hereunto subscribed my name this 22nd day of April, 1916.

ZOPIE A. VIŠEK.
